CLAIM

The ornamental design for an exercise apparatus, as shown and described.

DESCRIPTION

[FIG. 1 is a perspective view of an exercise apparatus showing our new design;]

[FIG. 2 is a front view of the design of FIG. 1, wherein the opposite side of the exercise apparatus is a mirror image of the front side;]

[FIG. 3 is a top view of the design of FIG. 1;]

[FIG. 4 is a bottom view of the design of FIG. 1; and,]

[FIG. 5 is a side view of the design of FIG. 1, wherein the opposite side of the exercise apparatus is a mirror image of the side view.]

[The band is shown with a symbolic break in its length. The appearance of any portion of the article beyond the break lines forms no part of the claimed design.]

FIG. 6 is a perspective view of an exercise apparatus showing our new design;

FIG. 7 is a front view of the design of FIG. 6;

FIG. 8 is a rear view of the design of FIG. 6;

FIG. 9 is a top view of the design of FIG. 6;

FIG. 10 is a bottom view of the design of FIG. 6; and,

FIG. 11 is a side view of the design of FIG. 6, wherein the opposite side of the exercise apparatus is a mirror image of the side view.

The broken lines shown in the Figures are for the purposes of illustrating portions of the exercise apparatus which form no part of the claimed design.
